UNITED STATES PATENT OFFICE

133,701

DESIGN FOR A SHOE

Hans Henkel, Baltimore, Md., assignor to Dixon-Bartlett Company, a corporation of West Virginia

Application May 5, 1942, Serial No. 106,799

Term of patent 7 years

To all whom it may concern:

Be it known that I, Hans Henkel, a citizen of the United States, residing in Baltimore city, in the State of Maryland, have invented a new, original, and ornamental Design for a Shoe, of which the following is a specification, reference being had to the accompanying drawing, forming part thereof, in which:

I claim:

The ornamental design for a shoe, as shown.

HANS HENKEL.
